(57) **CLAIM**

I claim the ornamental design for a tray, as shown and described.

DESCRIPTION

FIG. 1 is a perspective view of a tray in accordance with my new design;

FIG. 2 is a top plan view of the tray of FIG. 1;

FIG. 3 is a bottom view of the tray of FIGS. 1-2;

FIG. 4 is a front elevation view of the tray of FIGS. 1-3;

FIG. 5 is a rear elevation view of the tray of FIGS. 1-4;

FIG. 6 is a left-side elevation view of the tray of FIGS. 1-5; and,

FIG. 7 is a right-side elevation view of the tray of FIGS. 1-6.

The portions of the tray shown in broken lines in the figures depict unclaimed environmental subject matter, are for illustrative purposes only, and form no part of the claimed design.

It will be understood that all lines in the drawings, including broken and solid lines, are intended to convey the full disclosure and variations of the designs and such variations shall be understood to be fully described herein.
